[57] **CLAIM**

The ornamental design for decorative building blocks for village landscape display, as shown and described.

DESCRIPTION

FIG. 1 is a perspective view of a decorative building block for a village landscape display showing my new design;

FIG. 2 is a left side view thereof; the right side view thereof being a mirror image and symmetrical to the left side view thereof;

FIG. 3 is a front view thereof;

FIG. 4 is a back view thereof;

FIG. 5 is a top plan view thereof;

FIG. 6 is a bottom view thereof;

FIG. 7 is a perspective view of another decorative building block for a village landscape display showing my new design;

FIG. 8 is a left side view thereof; the right side view thereof being a mirror image and symmetrical to the left side view thereof;

FIG. 9 is a front view thereof;

FIG. 10 is a back view thereof;

FIG. 11 is a top plan view thereof; and,

FIG. 12 is a bottom view thereof.
